(57) **CLAIM**

The ornamental design for a cable, as shown and described.

DESCRIPTION

FIG. 1 is a top, front, left perspective view of a first embodiment of a CABLE, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom, front, right perspective view of the cable of FIG. 1, shown in a second configuration with alternative connectors;

FIG. 8 is a bottom, front, right perspective view of the cable of FIG. 1, shown in a third configuration with alternative connectors;

FIG. 9 is a top, front, left perspective view of a second embodiment of a cable showing our new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom, front, right perspective view of the cable of FIG. 9, shown in a second configuration with alternative connectors; and,

FIG. 16 is a bottom, front, right perspective view of the cable of FIG. 9, shown in a third configuration with alternative connectors.

The broken lines depict portions of the cable that form no part of the claimed design.

(Continued)

The cable is shown with a symbolic break in its length. The appearance of any portion of the article between the break lines forms no part of the claimed design.
